UNITED STATES PATENT OFFICE.

JOHN P. GILLES, OF ASHLAND, OKLAHOMA, ASSIGNOR OF ONE-TENTH TO HARRY G. ROWLEY, OF STUART, OKLAHOMA.

LANDSIDE-PROTECTOR FOR PLOWS.

1,114,687.

Specification of Letters Patent. Patented Oct. 20, 1914.

Application filed April 14, 1914. Serial No. 831,773.

To all whom it may concern:

Be it known that I, JOHN P. GILLES, a citizen of the United States, residing at Ashland, in the county of Pittsburg and State 5 of Oklahoma, have invented certain new and useful Improvements in Landside-Protectors for Plows, of which the following is a specification.

The present invention relates to a land 10 side protector for plows, and has for its primary object to provide a device of this character which can be used in connection with either a breaking plow or a lister plow, and which embodies novel features of construction 15 whereby it can be adjusted so as to raise the heel end of the land side as the plow point becomes worn.

A further object of the invention is to provide a land side protector which is simple 20 and inexpensive in its construction, which can be used interchangeably upon a number of plows, which can be quickly placed in position or removed therefrom, and which serves both to protect the land side against 25 wear and to elevate the heel end of the land side as the plow point becomes worn.

With these and other objects in view, the invention consists in certain novel combinations and arrangements of the parts as 30 will more fully appear as the description proceeds, the novel features thereof being pointed out in the appended claim.

For a full understanding of the invention, reference is to be had to the following 35 description and accompanying drawing, in which:—

Figure 1 is a side elevation of a plow provided with a land side protector constructed in accordance with the invention. 40 Fig. 2 is an enlarged longitudinal sectional view through the land side protector, showing the heel end of the land side in position therein, one position being indicated by full lines, while the other positions are indicated by dotted lines. Fig. 3 is a transverse vertical sectional view on the line 3—3 of Fig. 2, and Fig. 4 is an enlarged detail perspective view of the land side protector, showing it detached from the plow. 45

50 Corresponding and like parts are referred to in the following description and indicated in all the views of the drawing by the same reference characters.

Referring to the drawings, the reference

character A designates a conventional form 55 of breaking plow which includes a land side 1, a share 2, and a point 3. The land side protector 4 is in the form of a shoe which is adapted to be fitted detachably to the lower edge of the land side at the heel end 60 thereof. The shoe is formed with a longitudinally disposed slot 5 which opens through the top and forward end thereof and is adapted to receive the land side of the plow, as indicated by Figs. 1 and 2. 65

The bottom of the shoe 4 may have the forward end thereof beveled upwardly as indicated at 6 so as to minimize the resistance of the attachment to the forward passage of the plow through the soil, and in 70 a similar manner the top of the shoe may be inclined downwardly at the forward end thereof, as indicated at 7. A series of steps 8 are arranged at the rear end of the slot 5, and the heel of the land side may either 75 rest squarely upon the bottom of the slot 5 or upon any selected one of the steps 8, as may be found most desirable. Any suitable means may be provided for clamping the attachment in position upon the land 80 side, although in the present instance a set screw 9 is shown as threaded within one side of the shoe so that it can be screwed into engagement with the land side, as indicated by Fig. 3. 85

Under normal conditions and with a sharp plow point 3, the shoe would be applied to the land side 1 with the lower edge of the latter resting squarely upon the bottom of the slot 5, as indicated by Fig. 1. When 90 the plow point became slightly worn, however, the heel end of the land side would be positioned upon the first step 8, thereby slightly elevating the rear end of the land side and correspondingly depressing the 95 point so as to compensate for the worn condition of the latter. When the point 3 became worn to a greater extent, the position of the attachment would be again shifted so that the heel end of the land side would 100 rest upon the second step 8. This would result in a still further elevation of the land side at the rear end of the plow and a correspondingly greater depression of the plow point. 105

It will thus be seen that the device not only serves to protect the land side against wear, but also admits of the heel end of the

land side being raised step by step so as to correspondingly depress the plow point and compensate for wear upon the latter.

Having thus described the invention, what I claim as new and desire to secure by Letters Patent, is:

A land side protector for plows including a shoe formed with a slot opening through the top and forward end thereof and adapted to receive the heel end of the land side, a series of seats being provided

within the slot for enabling the land side to be fitted within the slot in a number of positions, and means for clamping the shoe in position upon the land side.

In testimony whereof I affix my signature in presence of two witnesses.

JOHN P. GILLES.
